UNITED STATES PATENT OFFICE

PLINY CATUCCI, OF NEWARK, NEW JERSEY

DESIGN FOR A CHECK WRITER CASING

Application filed October 10, 1931. Serial No. 41,357. Term of patent 14 years.

To all whom it may concern:

Be it known that I, PLINY CATUCCI, a citizen of the United States, residing in the city of Newark, county of Essex, and State of New Jersey, have invented a new, original, and ornamental Design for a Check Writer Casing, of which the following is a specification, reference being had to the accompanying drawing, forming a part thereof.

In the drawing, the figure represents a perspective view of a check writer casing showing my new design.

I claim:

The ornamental design for a check writer casing, as shown.

PLINY CATUCCI.
